UNITED STATES PATENT OFFICE.

LIONEL F. BOWERS, OF COLUMBIA, PENNSYLVANIA, ASSIGNOR TO COLUMBIA MFG. CO., OF COLUMBIA, PENNSYLVANIA.

CUFF-PRESS.

1,109,508.

Specification of Letters Patent.

Patented Sept. 1, 1914.

Application filed April 23, 1912. Serial No. 692,707.

To all whom it may concern:

Be it known that I, LIONEL F. BOWERS, a citizen of the United States, residing at Columbia, in the county of Lancaster and State 5 of Pennsylvania, have invented a new and useful Cuff-Press, of which the following is a specification.

This invention relates to an improvement in cuff presses.

10 The primary object of the invention is to provide a cuff press in which the pressure is applied in a direct line.

A further object is to provide a movable cloth padded bed, heat being imparted to 15 the same by radiation and not by contact with a heating element.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made 25 within the scope of what is claimed without departing from the spirit of the invention.

In the drawings,—Figure 1 is a front elevation, a single press being shown, although it will be understood that the invention is 30 adapted for twin presses; Fig. 2 is a vertical section.

In the drawings, 10 designates the standard of the press, which is supported on the base 11. This standard is hollow and arranged 35 to receive the actuating mechanism for the movable press member. This mechanism consists of the vertically movable shaft 12, which is guided by the bearings 14 and 15 which are formed integral with the 40 standard, bearing sleeves 16 and 17 being inserted within said bearings. The shaft 12 is connected to the tubular link member 18 which receives the reduced end 19 of the thrust bar 20. A treadle 21 is pivotally supported 45 at the base of the standard, said treadle being formed with the segmental gear 22 which meshes with the segmental gear 24 of the lever 25, which is pivotally mounted on the shaft 26. A hollow link 27 is connected 50 to the lever 25, said link receiving the reduced end 28 of the thrust bar 20, the thrust bar being provided with the cross key 29 which moves in the slot 30 of the link 27. A coiled spring 31 movably spaces the 55 low links 18 and 27, said spring being of suf-

ficient strength to withstand the upward pressure of the hollow link 27. When the treadle is depressed and the lug 32 carried by the same comes in contact with the lug 33 of the lever 25, the sleeve will be raised 60 and the spring 31 will force the hollow link 18 upward, imparting upward movement to the shaft 12.

The hollow heating member 34 is provided with the extended boss 35, which is formed with a bore 36 which receives the upper terminal 37 of the shaft 12. This shaft is threaded as at 38 and receives the adjusting wheels 39 and 40, which are spaced from the standard by the spring 41. The 70 heating member 34 receives heat from the pipe 42, this pipe being connected to the heating chamber 43 by the pipe 44 and coupler 45, which permits the heating member 34 to move vertically, the condensation 75 being led from the chamber by the pipe 46, which is connected to the pipe 42, which is provided with the coupler 47, which permits upward movement of the heating member 34. The member 34 is formed with the 80 longitudinal bore 48, which receives the bed supporting plunger 49. This plunger is restricted in its movement in one direction by the nut 50 and in the other by the boss 51 formed integral and disposed interiorly of 85 the bed 52. The bed 52, which receives heat from the heating member 34, is of the usual configuration. This member is spaced from the member 34, being provided on its face, which is active to the garment which is 90 pressed, with padding 53. The heat which radiates from the member 34 passes through apertures 54 to this padding, thus heating the garment. The bed is manipulated by the bail 55, the bed plunger maintaining the 95 same at all times parallel with the heating element 34. Thus, as the heating member 34 is raised, the bed will be raised, and the garment arranged thereon will be pressed between the same and the stationary heating 100 member 56 which receives heat from the pipe 42. It will be noted by this construction that a straight line upward thrust will be imparted to the bed and the heating member and that the bed will be maintained at all times parallel with the heating member, the adjustment which is common in machines of this character for maintaining this parallel relation of the heating member and the bed being unnecessary.

105

115

What is claimed is:

1. A cuff press comprising a stationary heating member, a movable heating member, said members being maintained parallel at 5 all times, a perforated goods support, a plunger carried by said goods support, said movable member being bored to receive said plunger.
2. A cuff press including a stationary heating member, a movable heating member, a plunger supported by said movable member, a bed supported by said plunger, said heating member and said bed being maintained in fixed parallel relation, a thrust bar for imparting movement to said movable member, a lever arranged to actuate said said thrust bar, a treadle, and coacting lugs carried by the thrust bar and lever.
3. A cuff press including a movable heating member, a stationary heating member, a 20

bed carried by said movable heating member and in fixed parallel relation therewith, a shaft connected to said movable heating member, a hollow link pivotally connected to said shaft, a thrust bar extending within 25 said hollow link, a treadle, a segmental gear carried by said treadle, a lever, a segmental gear carried by said lever, said gears being in mesh, and a hollow link connected to said lever, said link receiving the end of the 30 thrust bar remote from the first mentioned hollow link.

In testimony that I claim the foregoing as my own, I have hereto affixed my signature in the presence of two witnesses.

LIONEL F. BOWERS.
